UNITED STATES PATENT OFFICE.

ARTHUR R. HAVENER, OF WALTHAM, MASSACHUSETTS, ASSIGNOR TO AMERICAN
TACKING HOOK CO., A CORPORATION OF NEW JERSEY.

TOP GAGE FOR LACING-HOOK-SETTING MACHINES.

1 091 572

Specification of Letters Patent. Patented Mar. 31, 1914.

Application filed May 22, 1913. Serial No. 769,136.

To all whom it may concern:

To all whom it may concern:
Be it known that I, ARTHUR R. HAVENER, a citizen of the United States, residing at Waltham, in the county of Middlesex and State of Massachusetts, have invented new and useful Improvements in Top Gages for Lacing - Hook - Setting Machines, of which the following is a specification.

10 The following is a specification.
This invention relates to a gage particularly adapted to be used in lacing hook setting machines to assist the operator in correctly positioning the upper of a shoe preparatory to setting the first lacing hook therein. The uppers of boots and shoes vary
15 considerably in size and form for different styles and sizes of shoes and it, therefore, becomes desirable, in order to adapt a lacing hook setting machine to correctly set lacing hooks in the proper locations in the uppers
20 of boots and shoes of different styles and sizes, that the positioning gage, known as the "top" gage, whereby the upper is correctly located for the setting of the first lacing hook therein, should be capable of a
25 large variety of adjustments to suit varying needs which may occur, and not only must these adjustments be capable of rendering the gage suitable for different sizes and styles of uppers, but also the adjustments
30 should be such as to overcome any inaccuracies or variations in the setting up of the device and attaching it to machines of different kinds for setting lacing hooks.

To these ends the invention consists in the combination and arrangement of parts set forth in the following specification and particularly pointed out in the claims thereof.

Referring to the drawings: It will be understood that my improved top gage is illustrated in connection with a machine of the class shown and described in U. S. Patent No. 977,090, issued to me November 29, 1910, machine for setting lacing hooks, to which reference may be had.

45 Figure 1 is a sectional plan of a portion of a lacing hook setting machine substantially like that described and illustrated in said Letters Patent, with my improved top gage attached thereto and with a right hand upper shown in full lines in position to have a lacing hook set therein, with the top gage adjusted to correctly position said upper for the insertion of the first lacing hook therein and a left hand upper shown in dotted lines
50 55 in correct position to have the first lacing

hook set therein. Fig. 2 is a sectional elevation taken on line 2—2 of Fig. 1. Fig. 3 is a sectional elevation taken on line 3—3 of Fig. 2.

Like numerals refer to like parts throughout the several views of the drawings. **60**

In the drawings, 5 is the frame of the machine.

6 is the punch, 7 a shoulder forming an annular clenching surface, constituting an anvil, on said punch. 65

8 is the punch carrier and 9 is the lacing hook carrier, whereby the lacing hook is carried up and passed through a hole punched in the upper 10 and clenched against the annular clenching surface 7, thus setting the lacing hook in the upper 10. 70

11 is a work support upon which the upper 10 rests during the punching, setting and feeding operations. 75

12 is a presser foot which is fastened to a vertical shaft 13 and by suitable mechanism is raised and lowered at the proper time to hold the upper against the work supporting plate 11 or to release it therefrom during 80 the feeding operation.

14 is an index pointer which is located on the front edge of a plate 15, said plate being adjustably fastened to the presser foot 12 by a screw 16 which extends through a slot 17 in said plate and has screw-threaded engagement with the presser foot 12. This index pointer 14 is used to aid the operator in positioning a left hand upper, it being understood that the lacing hooks in this machine are set from the under side of the upper. 85 90

18 is a front edge gage adjustably fastened by means of a screw 19 to the frame of the machine. 95

20 is a top gage consisting of a rod 21 provided at its front end with an angular flange 22, forming a notch 23, which is adapted to engage the upper corner of the shoe upper 10, said shoe upper being located on the work support 11 and the lower face of the angular portion 22 of the top gage resting on the upper face of said work support. The top gage is adjustably mounted in ears 24, 25 formed on a carrier 26 and is slidable longitudinally in said ears, being held in adjusted position by a set-screw 27. 100 105

The carrier 26 is slidably mounted on a holder 28 and means are provided to move the carrier 26 on said holder 28 consisting 110

of a pinion 29 which meshes into a rack 30 formed on the carrier 26. The pinion 29 is rotatably mounted on the holder 28, being fastened to a spindle 31 journaled to rotate in said holder 28 and being provided with a handle 32 by means of which it may be conveniently rotated. The carrier 26 is arranged to slide in a groove 33 formed in one face of the holder 28 (see Fig. 3) and said carrier is held in said groove by a screw 34 which has screw-threaded engagement with the holder 28 and is provided with a washer 35 which extends partly across the groove 33 and is held in position by a spring 36 which encircles the screw 34 between said washer 35 and the head of said screw. By this construction the slideable carrier is held in position in the groove 33 on the holder 28, but may be readily removed therefrom when desired by removing the screw 34.

The top gage rod 21 not only has sliding engagement with the ears 24 and 25 on the top gage carrier 26, but projects through, and has sliding engagement with, the boss 44 on the holder 28. Thus said rod assists in holding the carrier in operative position on the holder.

The holder 28 is rotatably mounted upon a stud 37 fast to a bracket 38, said bracket 30 being fast to the frame 5, and said stud has screw-threaded engagement with the bracket 38, whereby said holder may be clamped to said bracket. The stud 37 projects through a slot 39 in an arm 40 which extends laterally from the body portion of the holder 28 and forms a part thereof, so that said holder is thus mounted upon a vertical pivot 37 and is rotatable thereon as well as adjustable laterally thereof.

40. The end 22 of the top gage 21, it will be noted, is adapted to engage the upper edge of the shoe upper 10 between the pivot 37 and the anvil 7, and by this relative arrangement of the parts a very extended variety of 45 positions may be assumed by the end 22 of the top gage by swinging the holder 28 about its pivot 37, and a still further variation of such positions may be obtained by moving the holder laterally with relation to 50 said pivotal stud 37, this movement being obtained by loosening the stud 37 and sliding the arm 40 along said stud lengthwise of the slot 39. A further variation of the 55 position of the end 22 of the top gage with relation to the anvil and with relation to the upper may be obtained by loosening the set-screw 27 and sliding said top gage along in the ears 24 and 25 and then clamping it to the carrier by tightening said set-screw 60 27. These various adjustments are utilized to set the top gage in position for different styles and sizes of uppers and also such variations are used for fitting or adjusting the top gage to different styles, sizes and shapes 65 of machines, the intention being finally to

have the top gage set with accuracy for different sizes of uppers of a certain class by means of the index plate 41 which is fastened to the holder 28 (see Fig. 2) and is provided with graduations 42.

Upon the carrier 26 a single index mark 43 is provided and when the parts are all adjusted to their proper positions, that is, the holder and the carrier, the top gage can be moved to set the end 22 thereof in proper location to correctly position different sizes of uppers by rotating the handle 32 and thus moving the carrier by means of the pinion 29 and rack 30 to such a position that the index mark 43 will align with the proper graduation on the index plate 41 for the size of upper which is to have lacing hooks set therein.

The general operation of the device hereinbefore specifically and to some extent in general described is as follows: A right hand upper 10 is placed upon the work support 11, with its front edge contacting with the front edge gage 18 and with its upper corner engaging the notch 23 in the front end of the top gage 21. This locates the right hand upper in proper position to have the lowermost lacing hook set therein. For different sizes of uppers which have their particular numbers set forth on the 95 graduations on the index plate 41, the top gage 21 is set by rotating the pinion 29, by means of the handle 32, thus bringing the index mark 43 in alignment with the desired size, as marked in numbers upon the index plate 41. When a left hand upper is to have lacing hooks set therein, it is positioned as follows: The upper is placed with its front edge bearing against the front edge gage 18 and with its upper edge substantially in alignment with said index pointer 14. This locates the left hand upper in position to have the first lacing hook set therein and the upper is fed so as to have the lacing hooks set therein the proper distance apart by the punch 7 in a manner well known to those skilled in the art and particularly as set forth and described in said Letters Patent.

By making the top gage 21 adjustable in the carrier 26 the device hereinbefore described can be adjusted to overcome any differences of location of the different parts of the gage, carrier and holder caused by inaccuracy in workmanship or by differences in the machines to which the top gage is applied. By swinging the holder about its pivot 37 and by adjusting said holder laterally with relation to said pivot, a large variety in the different positions assumed by the end 22 can be obtained. Thus the device is rendered practical for different sizes, shapes and styles of uppers and also for different sizes and shapes of machines to which the device is to be applied. It will 180

be understood that the swinging of the holder upon its pivot 37 and the lateral adjustment thereof relatively to said pivot, and the adjustment of the top gage in its carrier 26 are all adjustments which are used to set the top gage correctly on new machines or different machines and for different classes, styles and shapes of uppers, but the index graduations 42 on the holder, together with the single index graduation 43, are utilized, together with the mechanism by which the carrier 26 is moved upon the holder, to set the top gage for different numbers or sizes of uppers, and where a certain style or class of upper is being used, the only change necessary in the position of the top gage is accomplished by rotating the handle 32 and the pinion 29 to set the carrier and its top gage rod 21 in proper relation to the size of upper which is to have lacing hooks set therein, the other adjustments and variations of the device being used comparatively seldom and only in cases where a great change in style of upper or form of machine is to be compensated for.

Having thus described my invention, what I claim and desire by Letters Patent to secure is:

1. A lacing hook setting machine having, in combination, a work support, a rod constituting a top gage adapted to engage the upper corner of a shoe upper located on said work support, a carrier upon which said rod is slidably mounted, a holder upon which said carrier is slidably mounted, said top gage rod having sliding engagement with said holder, and means to move said carrier and its top gage on said holder, and a vertical pivot upon which said holder is adjustably and rotatably mounted.

2. A lacing hook setting machine having, in combination, a work support, a holder

having a groove in one face thereof, a carrier slidably mounted in said groove, a top gage on said carrier adapted to engage the upper edge of a shoe upper located on said work support and means to hold said carrier in said groove consisting of a screw in threaded engagement with said holder, and washer on said screw projecting partly across said groove and engaging said carrier rier.

3. A lacing hook setting machine having, in combination, a work-support, a rod con-having a groove in one face thereof, a car- 55 rier slidably mounted in said groove, a top gage on said carrier adapted to engage the upper edge of a shoe upper located on said work support, means to hold said carrier in said groove consisting of a screw in 60 threaded engagement with said holder, a washer on said screw projecting partly across said groove and engaging said carrier and a spring on said screw between the head 65 thereof and said washer.

4. A lacing hook setting machine having, in combination, a work-support, a rod con-stituting a top gage provided at one end thereof with a notch adapted to engage the upper corner of a shoe upper located on said work-support, a carrier upon which said rod is slidably mounted, a holder upon which said carrier is slidably mounted, said top gage rod having sliding engagement 70 with said holder, and means to move said carrier and its top gage on said holder.

In testimony whereof I have hereunto set my hand in presence of two subscribing wit-nesses.

ARTHUR R. HAVENER.

Corrections in Letters Patent No. 1,091,572.

It is hereby certified that in Letters Patent No. 1,091,572, granted March 31, 1914, upon the application of Arthur R. Havener, of Waltham Massachusetts, for an improvement in "Top Gages for Lacing-Hook-Setting Machines," errors appear in the printed specification requiring correction as follows: Page 3, line 49, claim 2, after the word "and" insert the article *a*; same page and claim, line 52, strike out the syllables "rier"; same page, line 54, claim 3, strike out the word, syllable, and hyphen "rod con-" and insert the word *holder*; and that the said Letters Patent should be read with these corrections therein that the same may conform to the record of the case in the Patent Office.

Signed and sealed this 4th day of April, A. D., 1916.

[SEAL.]

R. F. WHITEHEAD,
Acting Commissioner of Patents.
